(57) **CLAIM**

The ornamental design for a hub with spout as shown and described.

DESCRIPTION

FIG. 1 is a perspective view of a faucet including a hub with spout of the new design;

FIG. 2 is a front elevational view of the hub with spout of FIG. 1;

FIG. 3 is a rear elevational view of the hub with spout of FIG. 1;

FIG. 4 is a left side elevational view of the hub with spout of FIG. 1, the right side elevational view being a mirror image thereof;

FIG. 5 is a top plan view of the hub with spout of FIG. 1; and,

FIG. 6 is a bottom plan view of the hub with spout of FIG. 1.

The broken lines are included for the purpose of illustrating portions of the article and form no part of the claimed design.

1 Claim, 4 Drawing Sheets
